DESIGN FOR A SERVING PLATTER

John G. Rideout, Cleveland, Ohio, assignor to
The Wagner Manufacturing Company, Sidney,
Ohio, a corporation of Ohio

Application August 5, 1936, Serial No. 64,263

Term of patent 14 years

To all whom it may concern:

Be it known that I, John G. Rideout, a citizen of the United States, residing in the city of Cleveland, in the county of Cuyahoga and State of Ohio, have invented a new, original, and ornamental Design for a Serving Platter, of which the following is a specification, reference being had to the accompanying drawing, forming part thereof.

The figure is a perspective view of a serving platter, showing my new design.

I claim:

The ornamental design for a serving platter, as shown.

JOHN G. RIDEOUT.
